UNITED STATES PATENT OFFICE.

GEORGE CLAUSING, OF PORTSMOUTH, OHIO, ASSIGNOR TO THE VULCAN BOX TOE
PROCESS CO., OF PORTSMOUTH, OHIO, A CORPORATION OF OHIO.

LAST.

1,085,669.

Specification of Letters Patent. Patented Feb. 3, 1914.

Application filed April 23, 1913. Serial No. 762,985.

To all whom it may concern:

Be it known that I, GEORGE CLAUSING, a citizen of the United States, residing in the city of Portsmouth, in the county of Scioto and State of Ohio, have invented certain new and useful Improvements in Lasts, (Case C,) of which the following is a specification.

The object of the invention is to produce a simple, strong and practical last which can be broken or flexed so as to facilitate the removal of the last from the shoe and so that the shoe will not be marred, broken or pulled out of shape during the removal of the last therefrom.

According to the present invention a last is constructed so that it will comprise a forward or toe part and a rear or heel part which are provided between them with a pair of bearing pins that extend transversely to the last. The toe and heel parts preferably bear directly against said bearing pins. Said toe and heel parts are held together by a connecting means that comprise a link and a lever to which said link is connected. The link is also connected to one of the last parts, preferably the toe part, and the lever is connected to the other last part, preferably the heel part. The last is also preferably provided on the heel part thereof with a latch which serves as a means for locking the lever whereby the said toe and heel parts can be held in the unbroken position. A spring is also provided for the purpose of forcing a portion of the latch in the proper direction for maintaining the toe and heel parts in pressing engagement with the bearing pins.

As showing a specific embodiment of the invention reference is made to the drawing forming a part of this specification and in which,--

Figure 1 is a vertically but longitudinally extending sectional view of the last showing the parts in extended or unbroken position. Fig. 2 is a similar view of the last showing the parts in the shortened, flexed or broken position. Fig. 3 is an end view of the heel portion of the last taken as on the line 3, 3 of Fig. 1, looking in the direction of the arrow.

The last A comprises the forward or toe part B, and the rear or heel part C. In the construction of the last the toe and heel parts are formed from a single piece of

wood and are integrally connected together. They are subsequently separated by transversely sawing as along the lines x y, y z and y z'. The portion defined by the saw-cuts z y and y z' is removed so that in the finished last the parts can assume the broken or flexed position shown in Fig. 2. At the juncture of the saw-cuts x y, y z and y z', namely, at y there is located the horizontally but transversely extending main bearing pivot pins D D' which are in the bored openings D. These bearing pivot pins D D' are secured in place to one of the last parts, for instance, the heel part C by means of the pins or nails d d'.

The heel and toe parts are connected together by the means E which comprise the connecting link E', the lever E² and the spring pressing means E³. One end of the link E' is directly connected to the toe part of the last and the other end of said link is connected to the lower end of the lever E² which in turn is pivotally connected directly to the heel part of the last C. The upper end of this lever is continuously pressed forwardly by the means E³ which comprises the spring E⁴ and the spring cap E⁵ that directly engages the upper or free end of the lever. When the last parts are in broken position as shown in Fig. 2 this spring is pressed inwardly a material distance and the free end of this lever is out of the way of the toe part B. When the parts occupy the position shown in Fig. 1 the upper free end of said lever extends beyond the surface C² of the heel part C a sufficient distance for the latch E⁵ to enter the space between the free end of the lever and the heel part whereby the heel and toe parts may be locked in the extended position shown in Fig. 1. This latch is secured to the heel part C by the screw e' and it will be manifest that by merely swinging this latch from the position shown in Fig. 1 to the position shown in Fig. 3, the last parts will be permitted to be moved to the broken position by merely applying sufficient force to compress the spring E⁴ when the free upper end of the lever moves rearwardly.

The heel and toe parts may be bored at b' and c' to provide a receiving space for the connecting link E' that is preferably of cylindrical formation. The heel portion is also provided with a vertically but lon-

5 longitudinally extending saw-cut e^2 for receiving therein the lever E^2 which is preferably of a flat piece of metal of proper size to substantially fit said sawed portion of the last.

- 10 The forward end of the connecting link E' is directly connected to the toe part of the last by the pin or rivet e^2 while the rear end of this link is directly connected to the lower end of the lever E^2 by the pin or rivet e^3 . The central fulcrum portion of the lever is directly connected to the heel part by the pin or rivet e^4 . The spring means E^3 is located within the bored opening e^2 and 15 the rear end of the spring E^3 rests directly against the bottom of said bored portion. It will also be noted that the line passing through the center of pin e^2 , at the forward end of the link, and through the center of 20 the pin e^3 , at the rear end of said link, is located below the center of the main bearing pins D and D' .

25 The improvements herein set forth are not limited to the precise construction and arrangement shown and described and may be embodied in various forms and modifications without departing from the spirit and scope of the invention.

I claim as my invention:

- 30 1. A last having a toe part and a heel part, a pin or pivot bearing between the parts and a connecting means extending from one of the parts to the other, said connecting means comprising a link that is 35 directly connected by a pin to the toe part and a lever which is directly connected to the heel part by means of a pin, the rear end of the link being directly connected to the lower end of the lever, the upper end 40 of the lever being engaged by means comprising a compression spring which tends to restore the heel and toe parts to normal position after the last has been broken, the heel part of the last also being provided with a locking means or latch which engages said lever so as to prevent the last from being broken while the lever is locked.

2. A last comprising a heel and a toe part provided with bearing pins between them, said parts having longitudinally extending 50 openings for receiving a connecting link and said heel part having a vertically but longitudinally extending saw-cut for receiving a lever, said last also comprising a link which is pivotally connected at its forward 55 end to the toe part of the last, a lever located in said saw-cut, which lever is pivotally connected to the heel part and also at its lower end to the rear end of said link, and spring means that engages the upper 60 end of said lever and which spring means tends to force the upper end of the lever forwardly so as to restore the heel and toe parts to unbroken position after they have been moved from said position, the link being arranged so that the line passing through the centers of the pivot pins at the ends of the link is located below the center of the bearing pins between the heel and toe parts.

3. A last comprising a heel part and a 70 toe part which can swing relative to each other about a transversely but longitudinally extending axis, said parts being connected by a means which comprises a longitudinally extending link that is located below the said axis, said means also comprising a vertically extending lever, the forward end of said link being connected directly to the toe part of the last, the rear end of said link being pivotally connected to the lower 80 free end of said lever that is in turn pivotally connected to the heel part of the last, the last also being provided with a locking means which engages the upper free end of said lever whereby the parts of the last will 85 be maintained in unbroken position relative to each other.

This specification signed and witnessed this 17th day of April A. D. 1913.

GEORGE CLAUSING.
